TYPEWRITER

Gino Modigliani, Ivrea, Italy, assignor to firm:
Ing. C. Olivetti & C., Ivrea, ItalyApplication September 30, 1931, Serial No. 566,104
In Italy June 25, 1931

1 Claim. (CL 197—30)

This invention relates to typewriters in which the characters are typed on the paper rolled over a cylinder by means of levers moved by the pressure exerted on the keys of the key-board by the fingers of the typist, with interposition of an inked ribbon.

Its object is a new arrangement of levers obtaining a visible print, in which the types are carried at the end of levers, pivotally mounted and oscillating as in most typewriters, around a pin: but in which instead of impressing a great speed to the type-bar-lever so that the type strikes the paper with force acting in the way of a minute hammer, said type-bar-lever, after having covered a part of its swing, from the position of rest, at a high velocity, slows down rapidly towards the end of said swing, coming in contact with the paper at a very limited speed and consequently without a blow, obtaining subsequently the impression by pressing strongly the types upon the paper. In such a way percussion is replaced by pressure, avoiding the noise of the blow of the type against the cylinder on which the paper is wound and thus securing a silent operation of the typewriter.

The accompanying drawing refers to a typewriter with "standard" key board in which each type-bar-lever carries two different signs; of course the invention may be applied to typewriters in which each of said levers carries either a single sign or more than two. Both the drawing and the specification are limited exclusively to the parts and members concerning the present invention, leaving out all the other parts of the typewriter, so that in Figure 1, showing a side view of the typewriter in its position of rest and in Figure 2 showing the same in the position of work, is only represented the set of levers transmitting the motion from the key on which the finger of the typist presses, to the type-bar-lever.

In said system of levers an important feature is the fact that each lever of the system describes a plane motion and that all forces applied to said lever act in the plane of motion. Thus there are, with regard to the levers, no cross-stresses which would cause friction in the pins, making the operation of the typewriter less even and quick.

On examination of the drawing it may be seen that key 1 on which the finger of the typist strikes, is carried by a lever 2 pivotally mounted on a steel wire 3 carried by a plate 4, extending for the whole front length of the typewriter and provided with notches at equal distances, in which are lodged the various levers of the keys. Said wire hinge 3 is arranged horizontally, so that

levers 2 all move in parallel planes, at right angles to the axis of the cylinder on which the paper is laid.

A spring 5 maintains lever 2 in its rest position, whilst two stops 6 and 7 limit its stroke brought about by the finger's action. The end 8 of lever 2 operates a bell-crank lever 9, pivotally mounted on a steel wire 10, carried by a plate 11, provided also with notches in which are lodged levers 9 and consequently similar in arrangement to plate 4.

Each lever 9 lies and moves in the plane of the corresponding lever 2, and the motion is transmitted between the two levers with variable ratios, because at the beginning of the motion the key-lever operates the extremity of the arm of the bell-crank lever, whilst at the end the point of contact between the two levers moves on very near to pin 10 of lever 9.

Thus the inertia of the system is gradually overcome by a very slight effort of the typist, increasing then gradually the angular velocity of lever 9.

By means of a pull-rod formed by two members 12 and 13 connected by a threaded part in order to adjust its length, the motion of lever 9 is transmitted to a lever 16 swinging about pin 17 and carried by a plate 38, provided as usual with slots for lodging the levers. The pull-rod 12—13 is pivoted in 14 on lever 9 and in 15 on lever 16; as will be explained hereafter it is convenient to design the pins of said pivots spherical, so as to allow the pull-rod to incline somewhat on the plane of the levers. Lever 16 carries a fixed pin 35 which can move a slot 18 cut in a lever 19 swinging around pin 20. Pin 20 is carried by an angle plate 21 swinging in its turn around pin 22, carried by plate 23 and subject to be adjusted by means of two screws 24 and 25 which can allow to said plate 23 slight displacements, fixing it finally in the required position. The object of such an adjustment will be disclosed hereafter.

The free end of lever 19 operates by means of pin 26 a link 27 hinged at its other end on a pin 28 carried by the type-bar-lever 29. This lever 29 swings around pin 30, formed by a steel wire carried by a circular plate 31, whose centre is located, as usually done in typewriters with radial arrangement of levers, in proximity to the point in which the types strike. Lever 29 carries on its free end the types 32 and in its rest-position, rests on a cushion 33 in felt or in any other proper material.

The paper on which the typing is done is rolled

as usual on a cylinder 34 against which the type 32 is brought to press.

As stated, as the type-bars all have to impress the type at the same point, they have the pins 5 arranged on a circumference and move in radial planes, therefore only the type-bar arranged in the middle plane of the levers system will be in the same vertical plane of the corresponding key-lever, whilst all other type-bars, will move in 10 planes more or less inclined relatively to the corresponding key-lever, and more so the further the latter is from the middle type-bar.

In order that the forces operating on each lever may all act in the plane of the same, it is 15 evidently necessary that all the links 27 and all the levers 19 and 16 should move all of them in the plane of motion of the corresponding type-bar. Pins 17 and 20 are located on arcs of circles with their centres arranged on an axis going 20 through the centre of plate 31. As on the other hand key-levers 2 and bell-crank levers 9 are lying and move all in vertical planes, there follows that to avoid oblique stresses, every pull-rod 12-13 must operate approximately along the 25 intersection line of the two planes formed by each key-lever and its corresponding type-bar. Such a condition can be obtained by varying for each set of levers the distance between pin 10 and pin 14 which acts on the pull-rod altering 30 therefore the form and length of the arm of the bell-crank levers 9 whose motion is transmitted by the key-levers 2, so as to cause all pull-rods 12 to accomplish exactly the same stroke.

Particularly in the lateral sets in which the 35 angle formed by the plane of the type-bar and the plane of the corresponding key-lever is greater, the pull-rod during its motion will shift, however slightly, away from the intersection line of said two planes.

40 It is therefore convenient that, as stated above, the pins should be spherical thus allowing said displacement without injurious stresses.

It is now possible to see how the system operates: On pressing key 1, motion is transmitted 45 from the bell-crank lever 9 and by pull-rod 12-13 to lever 16, which will swing around its pin 17 with a varying angular velocity, depending on the design of the transmission of motion between levers 2 and 9. By means of its pin 35 en- 50 gaging in sector 18, lever 16 causes lever 19 to swing around pin 20, moving from the position shown in Fig. 1 to that shown in Fig. 2.

By this rotation lever 19, through link 27, causes the rotation of the type-carrying lever 55 around pin 30, which latter lever moves from its rest position to the printing position (Fig. 2).

It should be noted that the motion of lever 19 is transmitted to the type-carrying lever with a ratio varying according to a trigonometric law. 60 In fact lever 19 and link 27 form a "knuckle-joint" mechanism, because the two members, which in the starting position are almost at right angles to each other, at the end of their swing, have their pins 20-26-28 in alignment, that is 65 in "dead centre" position, in proximity of which the angular displacements of lever 19 have a decreasing influence on the displacement of point 28. It is evident in fact that if we suppose to divide in a certain number of equal parts the total swing of lever 19, to each single and subsequent equal angle of rotation correspond in the type-bar-lever 29, angles of rotation decreasing progressively according to a trigonometric law.

70 It may now be seen with what law motion is 75 transmitted from pin 35 to lever 19. The ar-

angement of slot 18 is such that at the outset the motion is transmitted rather slowly with positive acceleration. In fact pin 35 in the first part of its swing approaches pin 20 around which swings lever 19, and therefore the angular displacements of lever 19 for a certain constant angular rotation of lever 16 will go increasing. Then pin 35 moves again away from pin 20, thus causing a decrease of angular velocity of lever 19, which decrease is rapidly enhanced by the 10 particular form of the slot, which, when pins 20-26-28 are near to dead centre, combines approximately with a circular slot having its centre in point 17 and having a mean radius equal to the distance between points 17 and 35, so that a 15 further rotational motion of lever 16 will have no appreciable action on the type-bar-lever.

As shown in the drawing, the slot in the lever is formed of a straight followed by a circular part, of course this particular form may be subject to 20 alterations according to the law with which motion has to be transmitted from lever 16 to lever 19, that is according to the desire of having a more or less sensitive positive acceleration at the beginning and negative acceleration of the end 25 of the swing. Of course the more the last part of the slot will approach the circular form, with its centre falling in point 17 in its motion, the slower will be the motion with which the type carried by lever 29 will approach cylinder 34 and 30 vice versa, the greater will be the pressure which it will exert, as it covers a very slight displacement for a large swing of lever 16.

There will therefore be no striking of the type 35 on the paper, because said type will bear against it slowly and the impression will be obtained through the great pressure developing in the further displacement which the levers complete up to the dead centre position, that is until points 20-26-28 are in alignment.

A spring 36 which recalls lever 16 is provided in order to retrieve the set in its rest position; also in order that said lever may not reach the end of the slot on account of too great an impulse on the part of the typist's finger, striking 45 against said slot's end, a cushion 37 of felt, rubber or other proper material, is provided: against this comes to bear said lever 16 through a part conveniently bent from it.

In order to adjust correctly for each type-carrying lever, the pressure with which it should bear 50 against the cylinder pin 20 of lever 19 is carried in a particular manner.

Said pin 20 is carried in fact by the angle piece 55 21 pivoted around pin 22 and whose position can be adjusted and then blocked by the setting-screws 24 and 25. The position of pin 20 is chosen in such a way that the straight line connecting pins 22 and 20 results almost at right angles with the straight line connecting pins 20-26-28 60 when these are in alignment, namely in the printing position.

With such an arrangement, on acting upon the two screws 25 and 24 and causing the angle plate to rotate somewhat, it is possible to shift slightly 65 the position of point 20, approximately along the line connecting pins 20-26-28, thus adjusting the pressure upon the paper. This adjusting device is given by way of example, and can of course be replaced by any other equivalent arrangement, for instance by a sliding piece adapted for shifting slightly pin 20 along the line connecting 20-26-28 when they are in alignment. Similarly also the way the motion is transmitted 70 from the key-lever to lever 16 is shown solely as 75

example, and can be replaced by any other arrangement with levers, slots, etc. adapted to obtain the transmission of motion preferably with variable ratios and with positive acceleration, in 5 order to overcome the inertia of the system more easily.

In above specification, it has been noted that lever 16 carries pin 35 moving in slot 18 of lever 19. Such an arrangement can of course be reversed, namely the pin can be fixed on lever 19 and the slot cut on the end of lever 16, without altering thereby the conditions of operation, as in this case also by properly designing the shape 15 of the slot, the transmission of the motion between the two levers can be obtained according to any desired law.

What I claim is:

In a typewriter, a frame, a type bar pivoted on said frame, toggle means connected to said type bar including a first lever pivoted on said frame having a slot therein, a key bar pivoted on said frame, means operated by said key bar to move said first lever including an element having a member engaging in said slot, said lever and element being so arranged and said slot being so shaped that said member can continue to move in said slot after said type bar reaches printing position, and an elastic cushion in the path of movement of said element against which said element strikes after the type bar reaches printing position to start the parts on their return move- 10 15 ment.

GINO MODIGLIANI.
